UNITED STATES PATENT OFFICE.

WILLIAM O. CHRISTENSEN, OF MARSHFIELD, OREGON.

CENTER-BOARD.

SPECIFICATION forming part of Letters Patent No. 276,353, dated April 24, 1883.

Application filed January 9, 1883. (No model.)

To all whom it may concern:

Be it known that I, WILLIAM O. CHRISTENSEN, of Marshfield, in the county of Coos and State of Oregon, have invented a new and useful Improvement in Center-Boards for Vessels, of which the following is a full, clear, and exact description.

The object of my invention is to provide a center-board for vessels that can be more readily operated, and which will give a greater area of resistance than center-boards of ordinary construction and arrangement.

Reference is to be had to the accompanying drawings, forming a part of this specification, in which similar letters of reference indicate corresponding parts in all the figures.

Figure 1 is a side elevation, partly sectional, of a vessel provided with my improved center-board. Fig. 2 is a transverse section at the keel, showing the board in the lowered position. Fig. 3 is a similar view, showing the board raised. Fig. 4 is a cross-section of one of the rods extending to the center-board. Fig. 5 is a cross-section through one of the wells on the line $\alpha\alpha$ of Fig. 3; and Fig. 6 is a detail showing the connection of the rods with the center-board.

A is the keel, and B the keelson, of the vessel. C is the well for the rods extending through the bottom of the vessel at each side of the keel, and closed over the top of the keelson to form a chamber, in which the rods and cross-bars rise and fall. From the top of the well tubes a extend to the top of the main deck, or to any suitable height.

b are rods extending through the wells C, and connected above the keelson by cross-bars c ; and the rods b may also be connected by suitable cross-rods at the bottom of the boards; and f are rods extending from the cross-bars c up through the tubes a , for use in raising and lowering the center-board. d are the boards attached to the lower ends of the rods b by means of bolts e , the holes through which the lower bolts e pass being oblong, so as to permit play of the bolts when either end is raised independent of the other. The rods b are of the form in cross-section shown in Figs. 4 and 5. Between the two end rods by which the center-board is raised and lowered are guide-rods h of similar construction and arrangement, these guide-rods, however, extending only to the top of the keelson. In

the lowered position of the center-boards, as shown in Fig. 2, they extend their full width below the keel, and when raised their lower edges are above the shoe on the keel, as shown in Fig. 3. If desired, the boards can be hung on a bolt at their forward ends and fitted at their after ends for being raised or lowered by means of the rod, as described, and, if desired, one board at one side of the keel may be used in place of two. The faces of the boards are to be filled out or made flush with the outside of rods b , to cause them to pass easily through the water. The rods f are to be provided at their upper ends with suitable devices for the attachment of tackle for raising the center-boards.

I do not confine myself to the exact form in cross-section of the lower parts of the wells C, as shown, as the same may be of any convenient form, and can be formed as guides for the rods b at the bottom side of the planking only, and may also be provided with stuffing-boxes for the purpose of keeping water from entering the wells. By this construction and arrangement of the center-boards a vessel is not weakened by the necessity of cutting away the timbers to receive the center-boards. The boards being entirely below the vessel, only the planking is cut to receive the tubing for the rods, and at the same time the board furnishes a large area of resistance, takes up no cargo room, and can be more readily manipulated.

I am aware that it is not new to place center-boards on each side of the keel, or to raise and lower a center-board by means somewhat similar to mine; but

What I do claim as new and of my invention is—

1. The combination, with the well C, the keelson B, and the keel A, of the tube a , extending to the deck, the rods b , connected above the keelson by bars c and at the bottom of the keel, and the rods f , extending from the cross-bars c up through tube a , as and for the purpose specified.

2. The boards d , having oblong holes, and thereby being provided with play on the lower bolts e when either end is raised independently of the other, as shown and described.

WILLIAM O. CHRISTENSEN.
